LOUIS B. HEEP, OF DENVER, COLORADO.

AMUSEMENT GAME.

1,169,257.

Specification of Letters Patent. Patented Jan. 25, 1916.

Application filed August 23, 1915. Serial No. 46,771.

To all whom it may concern:

Be it known that I, LOUIS B. HEEP, a citizen of the United States, residing at Denver, in the county of Denver and State of Colorado, have invented a new and useful Amusement Game, of which the following is a specification in such clear terms as will enable those skilled in the art to which it appertains to construct and use the same.

10 My invention relates to amusement-games, more particularly adapted for parks, places of amusement, fairs, carnivals, etc.

The object of my invention is to provide an amusement game comprising a constantly 15 slowly revolving or rotatable table upon which is carried in suitable spaced relation a series or plurality of appropriate figures or dummies capable of going through various movements at predetermined places after 20 passing out of one set of swinging doors and prior to entering another set of adjacent doors.

A further object of the invention is to provide the heads of the figures or dummies 25 with a suitable dunce-cap or other appropriate head gear adapted to be knocked off by means of suitable balls adapted to be thrown by amusement seekers during the interval the dummies are passing from one 30 set of doors to the other set.

A further object of the invention is to provide means to partly rotate one set of dummies at a predetermined place and subsequently returning them to their natural 35 position; means to cause another set of dummies to partly rotate and to preferably simultaneous therewith bow their heads at a predetermined place during their travel in exposed position; means to cause another set 40 of dummies partly to rotate at a predetermined place and preferably simultaneous therewith cause the dummies to move upward and then downward; and still further means to cause another set of dummies only 45 to move up and down at a predetermined place in the path of their travel. Other movements for the dummies too numerous to herein mention may be employed for the dummies if desired.

50 A still further object of the invention is to provide means to bring the dummies back to their natural position after having been moved, thus making them ready for their next movement.

55 A still further object of the invention is to provide a suitable scenic wall provided

with two sets of spring hinge supported doors so as to expose only a predetermined number of traveling dummies or figures at a time to be thrown at for the purpose of 55 knocking off their hats.

A further object of the invention is to provide means to hide from view the lower parts of the dummies or figures and the working parts of the invention.

With the above and other objects in view, the invention consists in certain new and novel combinations, constructions, and arrangements of parts as will be hereinafter more fully described and finally pointed out 70 in the claims hereto appended.

Referring to the accompanying drawings forming a part of this specification, wherein like characters of reference denote similar parts throughout the several views: Figure 1, 75 is a plan view of my amusement-game. Fig. 2, is a front elevation thereof with portions thereof broken away. Fig. 3, is a detail of the preferable construction of the dummy that only partly rotates and then resumes its 80 natural position again. Fig. 4, is a detail of the preferable construction of the dummies that partly rotate and bow their heads. Fig. 5, is a detail of the preferable construction of the dummies that partly rotate and 85 move up and down. Fig. 6, is a detail of one form of means for partly rotating the dummies during their travel and the means for subsequently bringing the dummies back to their natural position. Fig. 7, is a modification of the means shown in Fig. 6.

In carrying out the aim of my invention, I employ a suitable wheel-like rotatable table 1. Passing through the center of the table is a suitable supporting shaft 2, preferably mounted at its lower end in a suitable bearing and suitably supported at its upper end to hold the table 1 in its desired position. A suitable gear, preferably a bevel-gear 4 is secured to the shaft 2 near its lower end 100 and it meshes with a suitable pinion 5 secured to the driven shaft 6. The opposite end of shaft 6 is provided with a suitable belt-pulley 7 which is preferably driven by means of a belt 8 leading from a suitable 105 motor. Adapted to be mounted upon suitable casters 9 are a plurality of rotatable plates 10, 11, 12 and 13. These plates it will be observed are supported by means of the table 1. Suitably secured to the top of each 110 plate 10 are a pair of spaced supporting members 14 connected at their upper end

with the cross-head 15. Adapted to pass through the table 1 and each plate 10 is the dummy actuating-rod 16. The upper end of the rod 16 is provided with a suitable cross-arm 17 adapted to support suitable shoulder blocks or padded fillers 18, over which is adapted to be draped or placed an appropriate garment 19. Each dummy in the game is preferably provided with these 10 shoulder blocks 18.

Each dummy actuating-rod 16 is preferably provided with a longitudinal groove 16' into which is adapted to seat a set-screw 15' to cause the plates 10 and 13 to turn 15 with the rod when partially rotating the dummies. The upper extremity of the dummy actuating-rod 16 is provided with a suitable and appropriate block-head 20. The lower end of the dummy actuating-rod 16 is 20 provided with the outwardly projecting arm 21, held in a predetermined position by means of the coiled spring 22. The arm 21 is adapted to strike a suitable stop 23 during its travel at a predetermined place and 25 cause the plates 10 to turn until the arm 21 slips off of engagement with the stop 23. The spring 22 will return the arm 21, plate 10 and dummy to their natural position.

Secured to each plate 11 are a pair of opposed supporting arms 24 having their upper end open. A tubular guide member 25 is also supported by each plate 11 intermediate the guide-arms 24. Adapted to pass through the table 1, plates 11 and tubular 30 guide-members 25 is a dummy-head actuating-rod 26 having the inclined or bent bifurcated end 27. A bent head-lever 28 is loosely mounted upon the cross-arm 29. Arm 29 is adapted to pass through the guide-arms 24 35 and extend therebeyond like cross-arm 15 to form the shoulders of a dummy. The lower end of the bent head-lever 28 is provided with a slotted opening 30 and is connected to the bifurcated end 27 of rod 26 by 40 means of the pin 31. The upper end of the bent head-lever 28 is provided with a suitable block-head 32. A suitable coiled spring 33 is connected at one end to the plate 11 and at its opposite end to the bent head-lever 45 28 to normally hold the block-head 32 in its upright or natural position. The lower end of the block-head actuating-rod 26 is provided with a suitable caster 34.

A suitable turning-block 35 is secured to 50 the upper face of each plate 11. An angular arm 36 is also secured to and supported by the plates 11. A suitable caster 37 is secured to the lower end of each angle-arm 36.

Secured to the upper face of each plate 12 55 are the same dummy forming and actuating parts as shown and described in Fig. 3, of the drawing. The lower end of the dummy actuating-rod, in this instance, is preferably provided with a suitable caster 38. The plates 12 are each also provided with the

turning-blocks 35 and the angular-arms 36 provided with the casters 37.

Each plate 13 is provided with the same dummy forming and actuating parts as shown and described in Fig. 3, of the drawing, with the exception that the dummy actuating-rod 16 is provided with a suitable caster 39 at its lower end, as shown in dotted lines in Fig. 3, instead of the arm 21.

Each block-head is provided with a suitable and appropriate dunce-cap, cocked-hat, or any other suitable head gear 40. The head gear 40 is preferably connected to some part of the body of the dummy by means of a suitable cord, chain or other connection 41, so that when the hats are knocked off their respective heads they will not fall to the floor, but will hang from the dummy where it can be easily reached and replaced upon the block-head by an attendant for the 85 purpose.

In the path of travel of the turning-blocks 35, I place at some suitable place a suitable caster 42 secured to a suitable supporting post 43. When the turning-blocks 35 come 90 in contact with the caster 42 the block 35 turns the plates 11 and 12 until the angular-arms 36 assume the position shown in dotted lines in Fig. 1. When the arms 36 have reached this position by turning the plates 95 11 and 12, the blocks 35 leave the caster 42, as is manifest.

The arms 36 after having traveled with the table 1 for a suitable distance will strike and engage the inclined face 44 of stop 45. 100 As the table 1 rotates the caster 37 of arm 36 will be forced down the inclined face 44 of stop 45 until the plate and dummy have returned to their natural position, when then the roller 37 will be allowed to 105 pass the stop 45, as is manifest. A suitable inclined member or track 46 is suitably positioned under the table 1 in the path of travel of the casters 34, 37, and 39. This means causes the dummies to move 110 up and down and bow their heads, as is manifest.

Suitably positioned above the slowly rotating table 1 is a suitable scenic wall 47. Suitably mounted upon spring hinges 48 115 near one end of the scenic wall 47 and forming a part thereof in the path of travel of the dummies is a pair of outlet doors 49. Suitably mounted upon spring hinges 50 near the opposite end of the scenic wall 47 120 and forming a part thereof in the path of travel of the dummies is a pair of inlet doors 51. These doors are preferably allowed to work both ways as two way hinges are preferably employed.

The scenic-wall 47 and doors 49 and 51 125 may be so positioned with relation to the table 1 as to allow any suitable number of dummies or figures exposed on one side of the scenic wall and doors to be thrown at 130

with the object of knocking off the head gear. If a hat is knocked off it is readily easily replaced by an attendant stationed behind the scenic wall 47.

5 The modification shown in Fig. 7, of the drawing, shows how the turning-block and angular-arms 35 and 36, respectively, may be made or cast in one piece as indicated by reference characters 35' and 36' respectively, thus doing away with the plates mentioned for supporting the dummies.

The operation of my amusement-game is as follows: First the motor or other suitable power is started to impart a constantly slow rotating movement to the table 1. The dummies or plates 10, 11, 12, and 13 in their travel with the table 1 will force or push open the doors 51 as they come in contact therewith, as is manifest, thus at 15 all times having a plurality of constantly but slowly moving dummies or figures appropriate for the purpose on the outside of the scenic wall 47. The dummies mounted upon plates 10 will, at a predetermined 20 place be caused to partly rotate as the arm strikes the stop 23. The dummies or figures mounted upon the plates 11 will, when the turning-blocks 35 strike the caster 42 be turned or rotated slightly, preferably, 25 simultaneous with the bowing movement of the head of the dummies which is caused by the caster 34 coming in contact with the inclined track 46. When the caster 37 strikes the stop 45 the plates 11 and dummies mounted thereon will be forced back 30 to their natural position, as is manifest. The dummies or figures mounted upon the plates 12 will, when the turning-blocks 35 strike the caster 42 be slightly rotated and preferably simultaneous therewith the caster 34 will come in contact with the inclined track 46 causing the dummies or figures to move upward and subsequently move downward to their natural position. The dummies or figures mounted upon the plates 13 will, when the caster 39 comes in contact 45 with the inclined track 46 cause the dummies or figures to rise upward and then resume the natural position as the table 1 rotates. 50 The object of the game is to knock the hat off of the block-head of any of the exposed traveling dummies or figures during the interval of their coming out of one set of doors and their entering another adjacent set of doors carried by a scenic background or wall.

It will be remembered that the table 1 is constantly rotating at a suitable rate of speed, that the dummies are mounted thereon and moving therewith and further that the dummies are capable of going through various cutting-up movements appropriate for the game, which movements of the dummies adds spice and life to the game, as it 60 is harder to hit the hats of the dummies 65

while going through various movements while constantly moving than if they were merely rotating, or standing still at intervals.

I am aware that various slight changes 70 may be made in the form, construction, and arrangement of the several parts of my invention; that the dummies or figures may be made to go through various other movements than the ones shown and described, 75 hence I do not wish to limit myself to the exact construction of parts, arrangements and movements of the dummies or figures shown and described, but reserve the right to make the dummies go through any other 80 movements during their travel in an exposed position without departing from the spirit or scope of my invention or departing from the principles thereof.

What I claim is:

1. In an amusement game, the combination 85 with a revolving table, of a wall spanning said table, appropriate figures movably mounted upon said revolving table, and swinging-doors in the path of travel of said figures adapted to be opened for the passage of said figures.

2. In an amusement game, the combination 90 of a constantly revolving table, a scenic wall spanning said table, a plurality of appropriate figures mounted upon said revolving table, swinging-doors arranged in said wall adapted to be opened for the passage of said figures, and means of subjecting said figures 95 to various movements during a period of their travel in each revolution of said table.

3. In an amusement game, the combination 100 of a constantly revolving table, a stationary wall spanning said table, a plurality of swinging doors arranged in said wall adjacent the outer edge of said revolving table, a series of appropriate figures mounted upon 105 said table in alignment with said swinging doors and adapted to travel with said revolving table, means of subjecting each series of figures to a different movement during a period of their travel in each revolution of the table, and appropriate head-gear for each figure adapted to be knocked off if possible during a period of travel in 110 each revolution of the revolving table.

4. In an amusement game, the combination 115 of a constantly revolving table, appropriate dummies movably mounted upon said table, a stationary wall spanning said table, swinging doors arranged in said wall adapted to be opened by said dummies, and an appropriate head-gear for each dummy adapted to be knocked off if possible during a period of their travel.

5. In an amusement game, the combination 125 of a constantly revolving table, a plurality of differently constructed dummies movably mounted upon said table near the edge thereof and adapted to be arranged in spaced re- 130

lation with one another, a wall spanning said revolving table, swinging doors arranged in said wall in the path of travel of said dummies and adapted to be opened by 5 means of the dummies coming in contact with them, means of subjecting said dummies to various movements during a period of their travel in each revolution of the table, and an appropriate head-gear for each 10 dummy adapted to be knocked off if possible during a period of travel in each revolution of the table.

6. In an amusement game, the combination of a constantly revolving table, a stationary 15 wall spanning said table, swinging doors arranged in said wall, a series of appropriate figures movably mounted upon said table in alignment with the swinging doors, which doors are adapted to be opened by said figures, means of subjecting a constant 20 procession of said figures to various movements during a period of their travel in each revolution of the table, and an appropriate head-gear for each dummy adapted to be knocked 25 off if possible during a period of travel in each revolution of the table.

7. In an amusement-game, the combination of a constantly rotating table, said table being of wheel-like construction, a plurality 30 of rotatably mounted plates supported in suitable spaced relation upon said table, an appropriate dummy carried by each plate, means for imparting a rotary-oscillating movement to said plates at predetermined 35 points along their travel, and means of subjecting said dummies to various movements during a period of their travel in each revolution of the table.

8. In an amusement-game, the combination 40 of a constantly rotating table, a scenic wall spanning said table, a plurality of dummy supporting plates, appropriate dummies carried by said plates, means of subjecting a plurality of said plates and dummies to a 45 rotary-oscillating movement, means to prevent rotary-oscillating movement of a plurality of said plates and dummies, means of subjecting a plurality of said dummies to an up and down movement, and means of 50 subjecting the heads of a plurality of said dummies to a bowing movement at a predetermined point in the path of travel.

9. In an amusement-game, the combination of a constantly rotating table, appropriate 55 figures arranged in suitable spaced relation

on said table, a scenic-wall separating a plurality of said figures from view during a part of their travel with the table, means of subjecting a plurality of said figures to a rotary-oscillating movement, means of subjecting a plurality of said figures to a rotary-oscillating movement and the heads thereof to a bowing movement, means of subjecting a plurality of said figures to a rotary-oscillating and up and down movement, means 60 of subjecting a plurality of said figures to an up and down movement only, and an appropriate head-gear for each figure adapted to be knocked off if possible during its travel while in an exposed position. 70

10. In an amusement game, the combination of a revolving table, a wall spanning said table, appropriate figures movably mounted upon said table, swinging-doors arranged in said wall adapted to be opened by said dummies to permit of their passage therethrough, and an appropriate head-gear for each dummy adapted to be knocked off if possible during a period of travel in each revolution of the revolving table. 75

11. In an amusement device, the combination of a revolving table, a wall spanning said table, appropriate dummies movably mounted upon said revolving table, swinging-doors in the path of travel of said dummies adapted to be opened for the passage of said dummies, and appropriate head-gear for each dummy adapted to be knocked off if possible during a period of travel in each revolution of the revolving table. 85 90

12. In an amusement device, the combination of a revolving table, a wall spanning said table, appropriate figures movably mounted upon said table, two sets of swinging-doors arranged in the path of travel of said figures adapted to be opened for the passage thereof, and appropriate head-gear for each figure adapted to be knocked off if possible subsequent to the passage of the figures through one set of swinging-doors 100 and prior to their passage through the other set of swinging-doors.

In testimony whereof, I have hereunto signed my name to the specification in the presence of two subscribing witnesses.

LOUIS B. HEEP.
